Primary Examiner — Robert M Spear*Assistant Examiner* — Darcey E Heflin*(74) Attorney, Agent, or Firm* — Ballard Spahr LLP**CLAIM**

The ornamental design for a wound pad, as shown and described.

DESCRIPTION

FIG. 1 is a perspective view of a wound pad showing our new design;

FIG. 2 is a perspective view thereof;

FIG. 3 is a perspective view of a second embodiment of a wound pad showing our new design;

FIG. 4 is a perspective view thereof;

FIG. 5 is a perspective view of a third embodiment of a wound pad showing our new design;

FIG. 6 is a perspective view thereof;

FIG. 7 is a perspective view of a fourth embodiment of a wound pad showing our new design;

FIG. 8 is a perspective view thereof;

FIG. 9 is a perspective view of a fifth embodiment of a wound pad showing our new design;

FIG. 10 is a perspective view thereof;

FIG. 11 is a perspective view of a sixth embodiment of a wound pad showing our new design; and,

FIG. 12 is a perspective view thereof.
